ROTARY KILN

Louis J. Mueller, Martinsburg, W. Va., assignor
to The Standard Lime and Stone Company,
Baltimore, Md., a corporation of Maryland

Application September 30, 1938, Serial No. 232,662

5 Claims. (Cl. 263—32)

This invention pertains to rotary kilns, and has for its main object the recovery of heat from the gases discharged from the kiln. This heat is now commonly lost, or is sometimes used in 5 waste heat boilers or for drying processes. Most of the recovery processes heretofore utilized have necessitated the employment of means exteriorly of the kiln, whereas the present invention recovers the heat from the exhaust gases within the kiln 10 itself or an integral portion thereof.

In the embodiment of the invention herein shown and described, a preheating chamber is employed as a part of the kiln. This chamber likewise acts as a reservoir for the material to be 15 treated in the kiln, and the exhaust gases from the kiln are drawn through such reservoir and the material therein by induced suction. Means is also provided in connection with said chamber and the adjacent portion of the kiln to ensure 20 adequate and definite feeding of the material from the preheating chamber into the kiln, the amount of feed varying with the speed of the kiln and certain other factors hereinafter mentioned.

Broadly stated, the invention comprises a rotary kiln in communication with a feeding and heat exchange chamber through a series of tubes or pipes extending from said chamber into the kiln, and means for exhausting the gases from the kiln through said pipes and feed chamber, where- 30 by the heat of the gases is absorbed by the material to be treated while it is within the tubes and the feeding chamber.

Another object of the invention is to provide means to preclude the material from being drawn 35 outwardly from the feeding chamber by the exhausting means. A further object is to provide means for periodically feeding an additional amount of material to be treated to the feeding chamber to maintain the same in its fully charged 40 condition, said means being automatically controlled through the rotation of the kiln and so constructed and operated as to prevent the escape of gases from the chamber or the indrawing of air therethrough except when the automatic mechanism is actuated to admit additional material to said chamber.

The drawing shows one embodiment of the invention wherein:

Figure 1 is a longitudinal sectional elevation 50 of a portion of a kiln interconnected with a suction fan to draw off the gases; and

Fig. 2 is a vertical sectional view taken on the line II—II of Fig. 1, with a portion of the wall of the feeding chamber and other elements broken 5 away to more clearly show the structure.

In the drawing, 10 denotes a portion of the rotary kiln which, as usual, is slightly inclined from the feed end toward the discharge end to ensure gravity feed of the material therethrough and the proper discharge therefrom. It will be supported and driven in the usual manner and it is not deemed necessary to fully illustrate such parts as they have nothing to do with the present invention. 5

At the head end of the member 10 a cylindrical feeding chamber is provided. In the structure shown in Fig. 1, said chamber is defined by the walls 11, 12 and 13, the wall 11 extending outwardly from the body of the kiln 10. Extending inwardly into the feed end of the kiln is a series 15 of cylindrical tubes 14 which are open at each end, the innermost ends being secured by welding or otherwise in openings formed in the wall 11. These tubes are shown as having the same inclination as the kiln 10 and are in free communication with the interior of the preheating and feeding chamber. While this chamber is shown in the drawing as being of a diameter larger than that of the kiln 10, its diameter may vary and, for instance, be the same as that of 20 the kiln 10. This being a mere matter of proportion, it is not deemed necessary to illustrate the same. 25

Extending outwardly from the wall 13, in line 30 with the axis thereof, is a nozzle or cylindrical member 15 which extends into a similar member 16 interconnected with the housing 17 of an exhaust fan. A suitable packing, as 20, will be interposed between these members to prevent the infiltration of outside air. A screen 18 extending 35 transversely of the combined preheating and feeding chamber precludes the indrawing of the material into the fan from said feed chamber. The mesh of the screen is determined by the size 40 of the material undergoing treatment. 40

In order to introduce material such as lime-stone, if that be the material to be treated, into the preheating and feeding chamber, the annular wall 12 is provided with an opening 19 (see more particularly Fig. 2) which is designed to be normally closed by a gate or valve 21 secured to a shaft 22, one end whereof extends outwardly of the feed chamber and is fashioned into a crank arm 23. An adjustable weight (or weights) 24 is mounted and secured upon the crank arm and tends to hold the gate 21 closed while said gate 45 is traveling with the chamber through the upper portion of its cycle. 50

Secured to a fixed element of the kiln-supporting structure 25 is a cam 26 which stands in the 55

path of the crank arm and contacts said arm as the kiln is rotating. When the parts are in the position shown in Fig. 2, the cam and crank arm are in cooperative relation and the gate or closure 21 is held in its open position. Immediately, however, the crank arm passes from the cam surface 26, the counterweight 24 will move the gate to its closed position, thereby closing off the opening from 19 and preventing further introduction 10 of material into the chamber.

To facilitate ready introduction of the material into the chamber through the opening 19, a hopper or spout-like element 27 is positioned to one side of the wall 12, the lower end of the hopper being contoured upon the same radius as that of said wall. Assuming that the crank arm has passed off of the cam surface, the counterweight will, as above mentioned, close the valve. As the kiln continues to rotate, the angle of repose of the material within the kiln will change and the material will pile up against the inner face of the gate or valve and thus hold it closed until the parts come to a position where the inner face of the valve is relieved of any pressure from the material within the chamber. This permits the cam surface 26 to function and open the valve to introduce another portion of the charge.

As the kiln and the combined preheating and feeding chamber are rotated, the material will 30 pass into the tubes 14 and will eventually work outwardly through their unobstructed ends onto the inner surface of the kiln 10. Not only does the arrangement ensure adequate and proper feeding of the material, but the material is, in a 35 sense, showered from the tubes transversely of the kiln into direct contact with the hot gases being drawn therefrom. As will be appreciated and seen upon reference to Fig. 1, the material falls across the mouths of the tubes through 40 which the hot gases are drawn so that the heat is abstracted in a most efficient manner. Moreover, this curtain of falling material, as it may be termed, falls past the discharge ends of all 45 of the tubes 14 other than the uppermost in the orbit so that the gas cannot short circuit through the apparatus. The path of the gases is indicated by the arrows in Fig. 1. Such heated gases will contact the material thus showered and thence pass through the tubes and the material 50 therein, into the preheating and feeding chamber and through the material therein, then through the screen 18 and through the nozzle 15 and, ultimately, into the intake housing 17 of the exhaust fan.

55 The rate of feed of the material into the kiln 10 depends upon several factors, the main one of which is the speed of rotation of the kiln. Another factor is the number of the tubes 14 as well as their length and diameter. The smaller 60 the diameter of the tubes and the smaller the number, the less rapid will be the feed. On the other hand, if the number be increased and the diameter enlarged, greater feed will obtain with the same rotative speed of the kiln.

65 The depth of the material in the feed chamber between the intake of the feed tubes and the screen 18 is a factor to be considered in the absorption of the heat from the gases which pass through the material being fed to the retort. 70 This depth is also limited by the characteristic of the material; that is, material of small void volume will require less thickness of material between the screen and the pipes to absorb the heat than one with a large void volume. The material in the feed chamber must, of course, be

maintained at such depth that the mouths at the intake of each of the tubes 14 will be covered, as is indicated in the drawing.

Actual use of a kiln constructed as above described has proved its success, and one is able 5 to regulate the feed and reduce the temperature of the gas to a point where it is profitable to install a motor-driven exhaust fan to suck the gases from the kiln through the resistance of the stone or other material in the combined pre-heating and feeding chamber and the feeding tubes.

By employing a suction fan connected to the head end of the kiln, one is enabled to speed the 15 operation. It is conceivable, of course, that the feeding chamber defined by the walls 11, 12 and 13, together with the tubes 14, may be utilized as a feeding means without the necessity of employing the suction fan. In other words, with 20 certain materials it may become advisable to operate the kiln in the absence of a fan and to merely vent the feeding chamber.

While I have shown and described the feed tubes as being cylindrical, they may be polygonal in cross section, and this form may have the 25 advantage of agitating the material to a greater degree as the gas passes through the material in the tubes. One such tube is indicated at 14a.

What is claimed is:

1. In a rotary kiln for the treatment of dry 30 material, a kiln section or chamber for receiving the material to be treated within the kiln, said section being enlarged circumferentially with reference to the diameter of the kiln; a plurality of tubular members extending from the forward 35 portion of said chamber directly into said kiln, said tubular members being substantially of the same length throughout the series and likewise of the same internal diameter throughout and free from obstruction from the intake to the discharge end thereof; a foraminous surface or 40 partition located adjacent the opposite end of the enlarged chamber, said chamber being in communication with the offtake of the kiln; means for introducing material into said enlarged chamber and maintaining it substantially full 45 of such material; and means for rotating the kiln.

2. A structure as set forth in claim 1, wherein the enlarged chamber is provided at its periphery with at least one opening in communication with 50 the interior of said chamber; a valve normally closing said opening; a fixed hopper located in line with said opening and normally closed by the circumferential wall of the chamber; and means for periodically opening the valve when 55 the opening in the enlarged chamber comes into registry with the discharge opening in the hopper, whereby material will pass from said hopper into the enlarged chamber and said chamber will be kept substantially full and short-circuiting 60 of the gases passing through the kiln to the offtake will be precluded.

3. In a rotary kiln, the combination of a kiln body cylindrical in cross section; a chamber located at the head end of said kiln, said chamber being of a diameter in excess of the diameter of the kiln proper and in communication with the offtake of the kiln; a series of tubular members extending into the kiln from said chamber and terminating within the kiln proper, said tubular 65 members being of the same diameter and length and free of obstruction throughout and affording the sole communication between the enlarged chamber and the interior of the kiln; a foraminous element located within the enlarged 70 75

- chamber for preventing passage of material therefrom other than the gases and dust which may inhere from the operation of the kiln; and means for introducing material to be treated into
- 5 said enlarged chamber and maintaining it substantially full at all times, said means being so related to the chamber as to prevent egress of gases therethrough when the parts of said means are in charging position.
- 10 4. In a rotary kiln for the treatment of dry material, the combination of an inclined kiln body; a circumferentially enlarged feed chamber located at the intake end of said body; a series of tubular members extending outwardly from
- 15 said chamber directly into the adjacent portion of the kiln and in free communication at their intake ends with the feed chamber, said tubular members being unobstructed from the intake to the discharge end thereof; a screen surface located within the feed chamber adjacent an off-take of the gases therefrom; and means for maintaining said feed chamber substantially full of material to be treated, whereby the material will be fed from said chamber simultaneously
- 20 into and through all of said tubular members aforesaid and thence from the tubular members directly into the body proper of the kiln.
- 25 5. In a rotary kiln for the treatment of dry
- material, a kiln chamber or section for receiving the material to be treated within the kiln, said section being enlarged circumferentially with reference to the diameter of the kiln; a plurality of tubular members extending from the forward portion of said chamber directly into said kiln, each of said tubular members being of substantially the same internal diameter throughout and free from obstruction from the intake to the discharge end thereof; a foraminous surface or partition located adjacent the opposite end of the enlarged chamber, said chamber being in communication with the offtake of the kiln; means for introducing material into said enlarged chamber and maintaining it substantially full of the material to be treated, said means comprising a valve normally closing an opening formed in the periphery of the enlarged chamber, a fixed hopper located in line with said opening and normally closed by the circumferential wall of the chamber, and means for periodically opening the valve when the opening in the enlarged chamber comes into registry with the discharge opening in the hopper, whereby material is passed from said hopper into the enlarged chamber; and means for rotating the kiln.
